Application August 20, 1946, Serial No. 691,803

11 Claims. (Cl. 146—85)

1

This invention relates generally to the class of harvesting machinery and pertains particularly to the harvesting of root crops, more particularly beets.

A principal object of the present invention is to provide a machine for harvesting root crops such as beets and the like, in which there is provided a novel mechanism for effecting the separation of the tops from the roots and for discharging the separated tops and roots in separate groups.

Another object of the invention is to provide a root harvesting and topping machine of the character stated having a novel mechanism for arranging the tops of the roots in proper position in advance of the plows whereby when the root is lifted from the ground, the top thereof will be held in a desired position so that it may be fed downwardly to the cutter to be properly and cleanly separated from the root.

A still further object of the invention is to provide in a harvesting machine for root crops, a novel topping mechanism which functions automatically in accordance with the size of the roots passing therethrough, to adjust the position of the cutting knife so as to sever the top from the root at the proper point.

Still another object of the invention is to provide in a root harvesting machine of the character stated, a novel mechanism associated with the top cutter whereby the means by which the root is moved relative to the top cutting knife, is automatically set into motion by pressure imposed upon a moving element by the beets entering the topper unit.

Another object of the invention is to provide in a harvesting machine of the character stated, a novel mechanism whereby certain parts of the machine such as the plows, conveyers, and the root topping mechanism and means for discharging the tops and roots separately, are all supported for up and down movement relative to the ground whereby proper adjustment of the plows relative to the ground and to the digging depth may be readily made.

Further objects of the invention will become apparent as the description of the same proceeds, and the invention will be best understood from a consideration of the following detailed description taken in connection with the accompanying drawings forming a part of the specification with the understanding, however, that the invention is not confined to a strict conformity with the showing of the drawings but may be changed or modified so long as such changes or

2

modifications mark no material departure from the salient features of the invention as expressed in the appended claims.

In the drawings:

5 Figure 1 is a view in side elevation of a machine constructed in accordance with the present invention.

Figure 2 is a view in top plan of the same.

10 Figure 3 is a horizontal section taken substantially on the line 3—3 of Figure 1 with parts removed to show more clearly details of construction.

Figure 4 is a rear end elevation of the machine.

15 Figure 5 is a vertical transverse section taken substantially on the line 5—5 of Figure 1.

Figure 6 is a vertical transverse section taken substantially on the line 6—6 of Figure 1.

20 Figure 7 is a view in elevation of the left hand side of the topping mechanism removed from the machine frame and from connection with driving or operating means.

Figure 8 is a horizontal section taken substantially on the line 8—8 of Figure 7.

25 Figure 9 is a view in top plan of the topping knife and carrying means therefor.

Figure 10 is a view in elevation of the topping knife and carrying means.

30 Figure 11 is a view in plan of the arm and plate unit which controls the elevation of the cutter.

Figure 12 is a view in elevation of the unit shown in Figure 11.

Figure 13 is a view in plan of the finger carrying unit upon which the topped beets are discharged from the topping unit.

35 Figure 14 is a transverse section taken substantially on the line 14—14 of Figure 13.

Figure 15 is a view in rear elevation of the control mechanism by means of which the rotary drum is put into operation.

40 Figure 16 is a view in side elevation of such mechanism.

Figure 17 is a view in rear elevation of the topping mechanism or topping unit together with the means at the two sides thereof for receiving 45 the beet tops and the topped beets.

Figure 18 is a vertical section taken substantially on the line 18—18 of the Figure 17, the view including the beet elevating units in side elevation.

50 Figure 19 is a view in top plan of the coacting spur gears by means of which the rotary cone is selectively coupled with and uncoupled from the power shaft.

Figure 20 is a section taken on the line 20—20 of Figure 19.

Figure 21 is a view in elevation of the right hand side of the topping unit as removed from the supporting frame and driving mechanism.

Figure 22 is a horizontal section taken substantially on the line 22—22 of Figure 21 and illustrating the manner in which a beet is discharged.

Figure 23 is a view in elevation of the outer side of the right hand guide wall showing the mounting thereon for the deflector plate.

Figure 24 is a sectional view taken substantially on the line 24—24 of Figure 23.

Figure 25 is a sectional view taken on the plane designated by the line 25—25 of Figure 17.

Figure 26 is a sectional view taken on the plane 15 designated by line 26—26 of Figure 17.

Figure 27 is a detail section on an enlarged scale of a portion of the platform and the lower 20 part of the cone structure shown in Figure 18.

Referring now more particularly to the drawings, the numeral 10 generally designates the main frame of the machine which is connected directly to the ground engaging wheels 11 and 12.

The numeral 11 designates the rear and main 25 wheels of the machine and these are mounted upon the main axle 13 which is supported in suitable bearings 14 which are secured to the frame 10.

The wheels 11 turn freely on the axle 13 and when the machine is running forwardly they are 30 automatically coupled for driving connection with the axle 13 by suitable overrunning clutches or ratchets 15. Since these overrunning clutches are of standard and well known construction and form no part of the present invention in themselves, it is believed that a detailed illustration and description of the same are not necessary. It will be understood that such clutches permit the backing of the machine without reversely 35 turning any of the mechanism which is driven from the axle.

At its forward end the frame 10 has the side members 16 turned inwardly as indicated at 17 and then extended forwardly into the spaced parallel portions 18 between which is secured a 40 draft beam 19 by which the attachment of the machine to a tractor or a team of horses, is facilitated. It will be understood, of course, that the invention is not restricted to the use of this specific type of hitch as it will be readily obvious that other means may be employed for attaching the mechanism to a draft machine or for hitching draft animals thereto.

Secured across the top of the draft coupling 45 19 is a bar 20 and disposed beneath this bar is a second bar 21. These bars are connected by the intermediate upwardly and outwardly diverging arms 22. The outer ends of the spaced bars 20 and 21 are suitably apertured to receive the vertical spindles 23 which are designed to turn on vertical axes and the lower end of each spindle is bent outwardly to form a stub axle 24 upon which a wheel 12 is mounted. Between each stub axle 24 and the lower bar 21 there is 50 interposed a spring 25 upon the spindle, which forms a cushion or shock absorber for the front end of the frame.

Upon the top of the draft hitch 19 there is provided the upstanding bracket 26 to which is pivotally attached the forward end of the steering shaft 27, the rear end support for which is hereinafter described.

The upper end of each spindle 23 has a spindle arm 28 secured thereto and these arms are connected by the coupling bar 29. A link 30 con-

nects one of the arms 28 with the steering finger 31 which is attached to the steering shaft.

Suitable bracing means 32 connects the lower bar 21 with the inturned portions 17 of the frame as shown in Figures 2 and 5.

To the side of the main frame, here shown as the left side, there is secured upon the inner side of the side bar or rail 16 of the frame, the short beam 33. The rear end of this beam is secured 10 to the rear cross member 34 of the main frame 10 as shown in the top plan view forming Figure 2.

Within the space between the short beam 33 and the adjacent side 16 of the main frame there is located a relatively large sprocket gear 35. This gear turns freely on the axle 13 by which it is supported.

Rearwardly from the sprocket gear 35 there is supported in suitable depending bearings 36 carried by the main frame, a short counter-shaft 37. Upon the outer end of the counter-shaft 37 is supported and secured the small sprocket gear 38 which is connected by the sprocket chain 39 with the large gear 35.

At its inner end the counter-shaft 37 has secured thereon the spur gear 40.

The hanging bearings 36 also support a shaft 41 upon which is mounted an intermediate idler spur gear 42. Also supported on this stub shaft 41 is a swinging bearing yoke 43 having rotatably supported therein one end of a swinging power distributing shaft 44. The opposite end of this shaft is supported in a corresponding swinging bearing 45 which is supported upon the opposite side rail 16 of the machine main frame 10.

Within the swinging bearing yoke the shaft 44 supports a spur gear 46 which meshes with the idler spur gear 42 so that the shaft 44 may receive power from the axle 13 through the sprocket drive and gears described.

The numeral 47 generally designates a clutch unit which comprises the two interlocking portions 48 and 49 and by means of which driving connection may be established when desired, between the sprocket gear 35 and the axle 13. One of the two portions of the clutch is secured to the gear 35 while the other portion is splined to the axle 13 and is movable relative to the gear carried portion so as to establish or disestablish as desired, the connection between the axle and the sprocket gear. The shifting of the splined portion of the clutch, here designated 49, may be effected through the medium of the usual forked actuating lever 50 which is pivotally mounted upon the short beam 33.

Fixed to the beam 33 and the opposite side rail 16 of the machine frame, to position over the longitudinal center of the machine, is the fixed arch frame generally designated 51. This arch frame supports at its center the bearing sleeve 52 through which the steering shaft 27 extends, the upper end of the shaft carrying the steering wheel 53.

Connected with the center of the arch frame 51 and extending rearwardly and downwardly to the rear portion 34 of the machine's main frame is an arched bracket member 54 upon which is supported a seat 55 for the operator of the machine.

At the front end of the machine, each side beam 16 of the main frame supports a bearing plate 56 and extending transversely of the main frame is a crank shaft 57, the offset crank ends 58 of which are oscillatably supported in the bearing plates 56 as shown in the top plan view forming Figure 2.

Disposed behind the crank shaft 57 within the main frame 10 is a shiftable or auxiliary frame which is generally designated 59. This auxiliary frame comprises the spaced parallel side portions 60.

At their front ends, the side portions 60 of the auxiliary frame, carry bearings 62 through which the crank shaft 57 passes.

At their rear ends the side portions 60 of the auxiliary frame carry the bearings 63 through which pass the shaft 44 which connects such side portions together.

Adjacent their rear ends the side portions 60 of the auxiliary frame are arched or curved upwardly as indicated at 64 so that this frame may have up and down movement without coming into contact with the main axle 13.

Forwardly of the arched portions 64 of the side members 60 of the auxiliary frame, a bracing arch 64' is secured to the auxiliary frame side portions 60 so as to give necessary rigidity to these portions to facilitate the proper support of the hereinafter described mechanism which the auxiliary frame carries.

Connected with each of the side members of the auxiliary frame 59 and extending downwardly and forwardly in convergent relation are two hanger bars 65 which may comprise extensions of the sides of arch 64'. At the lower end of each of these hanger bars 65, there is secured an earth-working plow 66 of the type suitable for use in connection with a machine of this kind, such plows being of standard design or construction. These plows 66 are suitably spaced so that they pass along the sides of a row of beets or other similar root vegetable and lift the vegetable from the ground without damage.

The numeral 67 generally designates the elevator mechanism by which the vegetable is raised to the desired position for discharge into the top-
per unit. This elevator comprises the two spaced parallel endless conveyers 68 which are arranged at an upward and rearward inclination and in addition are disposed in rearwardly converging planes as shown in Figure 6.

Each conveyer structure comprises the upper and lower sprocket shafts 69 and 69' respectively and the endless element 70 which passes around these shafts. The lower shafts 69' are rigidly supported in suitable bearings 70' which are carried by the convergent hangers 65. Extending upwardly from each of these bearings is a rigid beam 71 upon the upper end of which the upper shaft 69 is rotatably mounted. These beams 71 lie between the two runs of the conveyers of which they form a part.

The lower shaft 69' of each conveyer carries a gear 72 and in mesh with this gear is a gear 73 which is operatively attached to the lower end of a power transmitting shaft 74 which, at its other end, is supported in a bearing 75 carried at the rear end of the lower one of the adjacent hanger bars 65, Figure 3. The rear end of each power transmitting shaft 74 is directed toward the center of the shaft 44 and carries a miter gear 76 which is in mesh with a corresponding gear 77 carried upon the shaft 44, see Figures 3, 17 and 18.

The numeral 78 generally designates the top-
per unit. This unit is supported by the auxiliary frame 59 and is mounted upon the power distributing shaft 44 and is connected to the arches 64 of the side members 60 of the auxiliary frame by the transverse bar 79 which extends across and is secured between these side members.

The unit 78 comprises a bed-plate 80, Figure 75

18, and, lying above this bed-plate, a floor plate 81. Connecting these two plates is the lower end of an upwardly extending arm 82, the upper end of which is turned to extend rearwardly as indicated at 83.

Formed integral with the bed-plate 80 is a pair of foot bearings 84 which rest upon the power distributing shaft 44. Between these bearings the shaft 44 has secured thereto the miter gear 85.

Directly above the shaft 44 the plates 80 and 81 support the vertical stub shaft 86 which carries upon its lower end, below bed-plate 80, the miter gear 87 which meshes with the gear 85, while between the plates 80 and 81 this stub shaft has keyed thereto the spur gear 88. This gear together with the shaft 86 and the miter gear 87 are secured against axial movement.

Rearwardly of the stub shaft 86 the bed-plate has a bearing opening 89 through which extends a sleeve 90. Between the plates 80 and 81 the upper end of the sleeve 90 has secured thereto the spur gear 91. This spur gear 91 has a hub 92 upon its underside which has a flattened face 93.

25 The top surface of the bed-plate 80 under the hub 92 of the spur gear 91 is lowered as indicated at 94, Figure 27. This permits the gear 91 to drop below and out of mesh with gear 88 and provides the stop shoulder 95 with which 30 the flattened face 93 engages when the gear 91 is lowered, to hold the gear against turning.

Below the bed-plate 80 the sleeve 90 has a coil spring 96 therearound which bears at one end against the bed-plate and at its other end bears against a collar 97 carried upon the lower end of the sleeve. Thus the gear 91 is constantly urged to move downwardly by the spring and when the flattened face 93 of the gear hub comes into parallel relation with the shoulder 95 this 40 lowering of the gear is permitted to a sufficient extent to disengage the gear 91 from gear 88.

Extending through the sleeve and passing upwardly through the floor 81 and to and through the inturned upper end 83 of the arm 82, is a spindle 98. The sleeve 90 and the spur gear 91 are coupled to this spindle to turn therewith and to have sliding movement longitudinally thereon.

The numeral 99 designates the top-
per cone. This cone is hollow and is open at the top and at the bottom. The cone 99 is formed in a single piece, preferably from a single sheet of metal of suitable resiliency and it is longitudinally slit as shown in Figure 8, for the purpose about to be described.

50 The numeral 100 designates the wall of the cone and as is shown the material of the cone is shaped to provide a central sleeve 101 which encloses and is secured to the spindle 98.

Extending radially outwardly from the sleeve 60 101 is the web 102 which merges with the wall of the cone at one side of the division or slit which is designated 103 in Figure 22. The opposite edge of the division which constitutes the free edge of the material of which the cone wall is formed, is designated 104. Due to the resilient material of which the hollow cone is formed it will be readily seen that the wall of the cone adjacent to the free edge 104 may be readily flexed inwardly, the edge 104 moving radially along the web 102.

The sleeve 101 of the cone rests upon a suitable bearing collar 105 secured to the spindle and interposed between the sleeve and the floor sheet 106, which rests upon the floor-plate 81.

as shown. Since the sleeve is fixed to the spindle 98 and the spindle engages the bearing collar 105 it will be readily seen that the spindle is held against slipping downwardly and thus the two ends of the spindle are properly supported for rotation.

The numeral 107 generally designates a housing for the cone 99. This housing is spaced from the cone and is of the same form or configuration but it is divided to have the two openings 108 and 109. The opening 108 constitutes the inlet or entrance to the housing for the beets, as illustrated in Figure 8, while the opening 109 constitutes the exit from which the topped beets are discharged as illustrated in Figure 22.

As a result of dividing the cone housing to form the entrance and exit openings the housing is produced in two parts or sections, one of which is designated 110 and the other 111. The section 110 is secured to the arm 82 while the section 111 forms a part of a hereinafter described vertical guide flange which is attached to an arm 112 which is rigidly secured to the adjacent auxiliary frame side member 60 as shown in the side elevation of the machine forming Figure 1.

Forming rearward extensions of the cone housing sections 110 and 111, from the sides of the entrance opening 108, are the relatively wide rearwardly diverging guide flanges 113 and 114 respectively. These flanges are continued upwardly and forwardly above the cone and cone housing to form the wings 115 between which the upper end of the elevator 68 discharges.

In order to facilitate the proper movement of the beets over the top of the cone and cone housing and downwardly between the wings 115 and into the space between the guide flanges 113 and 114, the coacting inner runs of the elevator conveyors have suitably supported therebetween the spaced upper and lower guide walls 116 and 117. These walls are suitably curved toward the rear of the machine at their upper ends where they are positioned between the wings 115 as shown in Figure 18.

The lower end of the guide flange 113 is continued laterally, forwardly and downwardly to form a deflector 118, see Figures 7 and 17. This deflector overlies and is spaced from the floor 106 and a portion of the floor forwardly of the part thereof which is beneath the deflector, is cut out to form the top discharge opening 119, as shown in Figure 8.

The flange 114 carries upon its outer side a guide 120, Figure 21, in which is slidably mounted a rod 121 which extends downwardly and laterally across the lower edge of the flange 114 where it is secured to a downwardly inclined, forwardly and laterally extending shiftable deflector 122. A portion 123 of this deflector, see Figures 22 and 23, extends upwardly upon the inner side of the guide flange 114 against which it has sliding contact, and this carries a threaded pin 124 which passes laterally through a guide slot 125 and a slide plate 126, disposed against the outer side of the flange 114, where it receives a retaining nut 127.

A spring 128 connected between the upper end of the plate 126 and the guide flange 114 normally urges movement of shiftable deflector 122 upwardly. This shiftable deflector is of such width as to substantially close the lower end of the space between the flanges 113 and 114 so that any article moving downwardly between these

flanges will come to rest upon the shiftable deflector 122 and by imposing sufficient weight thereon will cause the deflector to shift downwardly.

Connected with the underside of the shiftable deflector 122 is the downwardly and forwardly curving arm 129. The rear edge of the bed-plate 80 is formed to provide a bearing sleeve 130 which is mounted for oscillation on a cam shaft 131. Each end of the cam shaft 131 carries a curved cam finger 132 which extends beneath and curves downwardly from and is arranged to have contact with the bottom face of the hub 92 of the vertically shiftable spur gear 91.

Also at one end of the cam shaft 131 is secured the upwardly extending crank arm 133 with which is pivotally connected the downwardly extending deflector plate carried arm 129.

It will be seen from the foregoing that when the shiftable deflector plate 122 is moved downwardly, the cam shaft 131 will be oscillated in a direction to raise the cam fingers 132 against the hub of the gear 91, thereby shifting this gear upwardly to compress and tension the spring 96 which normally urges the gear downwardly through the connection between the sleeve 90 and the gear 91. This upward shifting of the gear 91 will move it into mesh with the adjacent spur gear 88 which is driven from the power distributing shaft and which is constantly rotating while the machine is in motion. Thus downward movement of the deflector plate will automatically set the split cone into revolving motion within its housing.

Supported by the bracket 112 is a shaft 134. This shaft passes through the flanges 113 and 114, at the upper ends thereof and it supports upon the end adjacent to the flange 114, the sprocket gear 135. This gear is connected by the sprocket chain or other suitable driving connection 136, with a corresponding gear 137, supported on and secured to the power distributing shaft 44.

Between the flanges 113 and 114 is supported a feeder 138 by means of which the beets or other vegetables are moved downwardly toward the shiftable plate 122. This feeder comprises the two spaced parallel side boards 140 which are traversed at their upper ends by the shaft 134 and hang downwardly therefrom. Between the side boards the shaft carries the cylindrical wheel 141. At their lower ends the side boards 140 are connected by a cross shaft 142 on which is also carried a cylindrical wheel 143. Passing about these cylindrical wheels or rollers 141 and 143, is the endless belt 144. The power transmitted to the feeder 138 moves the endless belt 144 so that the inner run thereof moves downwardly in spaced relation with the wall of the split cone.

The lower end of the feeder 138 is swingable with respect to the cone and there is connected to one of the side boards 140, an end of a spring 145, the other end of which is attached to the adjacent fixed part of the housing such, for example, as the part or section 110.

At the left-hand side of the cone housing, forwardly of the end of the fixed deflector 118, there is secured to the adjacent fixed portion 110 of the housing, a vertical guide means here shown as being in the form of two tubular guides 146.

Slidably mounted in the tubular guides are the two posts 147 which are coupled together at their upper ends as shown in Figure 10.

The lower ends of the posts 147 are secured to a horizontally disposed knife or cutting blade 148.

This blade lies over the opening 119 in the floor

sheet and extends inwardly above the floor and between the latter and the lower edge of the cone 100. The cutting edge of the blade 148 is directed rearwardly or, generally, toward the space between the fixed and shiftable deflectors 118 and 122.

A substantial space is provided between the floor sheet 106 and the bottom edge of the split cone 100 so that the cutting knife 148 has a limited degree of vertical movement, always maintaining its cutting edge, however, directed rearwardly.

Forming a part of the outer end or shank portion of the knife 148 is a fingered deflector 149 which curves downwardly through the opening 119 so that material, in the form of beet tops which have been severed from the beet bodies, in passing under the knife blade, will be caused to fall directly downwardly.

Beneath the knife 148 is a vertical pivot 150 carried by the floor sheet 106. This pivot 150 carries the horizontal oscillating arm 151 which lies below the cone and for the major part within the circular area defined by the bottom of the cone as shown in Figure 8. The arm 151 extends in a direction generally lengthwise of the machine and the rear end of the arm carries the arcuate contact plate 152 which lies inside the cone and in relatively close proximity to the wall thereof. While the body of the cone or the wall 100 extends downwardly a sufficient distance to substantially enclose the contact plate 152, the web 102 terminates at a suitable elevation to permit it to move over the contact plate 152 when the cone revolves.

The opposite end of the arm 151 extends forwardly beyond the periphery of the cone base and has connected thereto one end of a link 153, the other end of which is pivotally attached to the depending arm 154 of a bell-crank lever indicated generally by the numeral 155 and pivotally mounted on the horizontal pivot pin 156 carried adjacent to a guide 146. The other arm of the bell-crank, designated 157, is connected by the link 158 with the posts 147.

A spring 159 connects one of the posts with a fixed part of the structure and normally urges the knife assembly downwardly to its lowermost position.

As will be readily obvious from the foregoing description when the arm 151 is oscillated by the engagement of the flexible portion of the cone against the arcuate plate 152, the bell-crank 155 will be oscillated to raise the knife against the action of the spring 159. Thus the degree to which the part of the cone wall adjacent to the web 102 is forced inwardly will determine the height to which the knife 148 will be raised in the manner and for the purpose hereinafter described.

Supported in a suitable manner beneath the top discharge opening 119 in the floor sheet 106, is a receptacle 160 into which the tops are received. However, this may be dispensed with and the tops may be discharged directly onto the ground.

At the opposite or right-hand side of the topper cone and housing there are positioned the vertical inner and outer wall plates 161 and 162 respectively which form a receiver into which the topped beets are discharged from the exit or discharge opening 109 of the cone housing.

The inner wall 161 is in close proximity to the cone housing and has its rear edge adjacent to and rearwardly of the exit or discharge opening

while the outer wall 162 extends forwardly a sufficient distance to prevent the beets being thrown outwardly beyond the side of the machine.

The lower part of the inner wall 161 carries a toothed screen 163 which coacts with an inwardly and downwardly inclined apron 164 to receive the beets. These elements 163 and 164 are also inclined downwardly and rearwardly so that the beets will gravitate to the rear of the machine to be discharged into the oscillatable receiving box 165. This box is pivotally mounted and is connected by a crank 166 and a rod 167, with a lever 168 which is located upon the fixed frame of the machine adjacent to the operator's seat 55, so that the operator may actuate the lever 168 to effect the tipping and dumping of the box 165, as desired.

The depth of penetration of the plows 66 into the earth is controlled by raising and lowering the movable frame 59. This action is under the control of a hand lever 169 which is pivotally supported upon the main frame 10 at 170. This pivot 170 is at the center of a toothed rack 171 with which the lever locking pawl 172 is detachably engaged under the control of the hand grip element and pull wire 173.

Connected with the lever 169 is the pull rod 174 which extends forwardly and is attached at its forward end to the crank arm 175 which is secured to the adjacent crank end 58 of the crank shaft 57.

When the hand lever 169 is pulled back the frame 59 will be swung forwardly and upwardly, this swinging movement being permitted by the swinging or hanging bearings 43 and 45 by which the power distributing shaft is supported. Thus the entire plow, elevator and topper assembly is raised and lowered upon oscillation of the hand lever 169.

The frame 59 is constantly urged to move or swing downwardly by the contractile spring 174a which, as shown in Figure 2, is connected at one end with the crank shaft and at its other end is secured to an adjacent part of the main frame 10. This spring constantly exerts a pulling action upon the crank shaft tending to make it oscillate or swing downwardly and thus lower the frame 59.

In the operation of the present machine, it is moved along the beet row with the plows 66 lowered to the proper depth to penetrate the ground on the two sides of the row of beets, to the proper depth to lift the beets from the ground. As the beets are lifted they will move back until engaged by the two conveyors of the elevator 68 and they will then be lifted or elevated to the wings 115. The beets will then leave the elevator and pass between the upper and lower guide walls 116 and 117 across the top of the cone and cone housing. As the beets move to the rear across the housing, the tops of the beets will fall back so that each beet will drop top down into the throat space formed between the guide plates 113-114, the cone 99 and the endless belt 144. After each beet has turned over and is directed top down into the throat it will be wedged between the inner downwardly moving run of the belt 144 of the feeder, and the adjacent wall of the rotatable cone and the feeder will force it downwardly, the lower part of the feeder moving back against the tension of the spring 145 during this operation.

The down movement of the beets will be against the wall of the cylinder which will be stationary until the beet, or beets, reaches the shiftable deflector 122. The downward force applied to the beets by the endless belt 144 will cause

the deflector 122 to be shifted downwardly, thus pushing down upon the arm 129 to effect the turning of the crank arm 133 so as to produce oscillation of the cam fingers against the bottom of the hub 92 of the shiftable spur gear 91.

The cam fingers move the spur gear 91 upwardly into mesh with the constantly moving gear 88 and this will start the cone revolving in a clockwise direction as indicated by the arrows in Figures 8 and 22.

As soon as the flanged edge 104 of the cone wall comes around into engagement with the beet lying between the feeder belt and the wall of the cone, the portion of the cone wall adjacent to the slot 103 will be flexed or forced inwardly as shown in Figure 8, and the beet, with its head directly downwardly, will be rolled in between the wall of the cone and the wall portion 110 of the cone housing. When this occurs the inwardly flexed portion of the cone wall will press against the end of the arcuate plate 152 and effect the oscillation of the arm 151. This action will produce oscillation of the bell-crank 155 and cause the knife 148 to be raised against the tension of the spring 159. The extent of upward movement of the knife 148 will be governed by the extent of oscillation of the arm 151 which in turn is governed by the extent of inward movement of the flexible portion of the wall of the cone. Thus it will be seen that the amount of movement of the knife is controlled directly by the size of the beet which is carried between the flexible cone wall and the fixed wall portion 110 of the housing.

As the beet is carried around, the head which extends down below the base of the cone, will be brought against the cutting edge of the knife and will be cut off. This cutting operation occurs when the head has reached the opening 119 in the floor plate and thus the severed top will drop through either onto the ground or onto a receptacle supported therebeneath.

The body of the beet minus the head or top will be carried around by the revolving cone until it reaches the discharge or exit opening 109 through which it will pass as shown in Figure 22, onto the screen 163 and from there into the receiving receptacle or box 165.

It will be seen that when the beets cease to enter the throat 139, pressure upon the shiftable deflector 122 will be relieved and the spring 128 will then move the deflector back to its raised position. This will disengage the cam fingers from the hub of the gear 91 and allow the spring 96 to pull the gear down out of mesh with the constantly rotating gear 88. Thus the rotation of the cone will be stopped until another beet passes down into the throat and is forced by the endless belt 144 into contact with the shiftable deflector 122.

What is claimed is:

1. A machine for topping such vegetables as beets and the like, comprising a conveyor for raising the vegetable to an elevated position, co-acting spaced members forming a receiver into which the vegetable is discharged top down from the conveyor, a cutter adjacent to the lower part of the receiver, a rotary element for moving the vegetable from the receiver toward the cutter, and linkage mechanism operated by the rotary element for elevating the cutter relative to the position of the downwardly directed top of the vegetable for effecting severance of the vegetable top from the vegetable body at a desired location.

2. A machine for topping root crops such as beets and the like, comprising a conveyor for

elevating the beet to a desired position, a downwardly constricted receiver into which the root is discharged top down from the conveyor, a topping knife supported for vertical movement at the lower part of said receiver, a rotary element for moving the roots and tops toward said knife from the receiver, and linkage mechanism operated by the rotary element connected with the knife and operating automatically in accordance with the size of the roots to elevate the knife relative to the top as the root and top are moved toward the knife.

3. A machine of the character stated in claim 2, with mechanism, including a deflector engaged and actuated by the root in its movement downward into the receiver, for setting into operation the said means by which the root and top are moved toward the knife.

4. Mechanism for topping beets and like root vegetables comprising a circular housing, a member disposed within the housing for rotation on an axis concentric with the housing, the member having a side wall in spaced relation with the housing wall, the housing having a side wall opening forming an inlet and a side wall opening forming an outlet, the housing being open at its bottom, means for positioning a beet top-down within the housing inlet opening, the rotary member having a portion of its wall yieldable whereby the beet may be rolled between the housing wall and the wall of the rotary member, a knife disposed below the open bottom of the housing and having a cutting edge toward which the top of the beet is moved by the rotating member, a lever and linkage operated by the inwardly flexed wall of the rotary member for shifting said knife to a desired elevation with respect to the beet top, the body of the beet being discharged through the housing outlet opening after severance of the top therefrom by the knife.

5. A topping mechanism of the character stated in claim 4, including a continuously operating power delivery gear, a mechanism operatively coupled with said rotary member and adapted to be shifted into and out of operative connection with the power delivery gear, and a movable deflector connected with said mechanism to be actuated by a beet introduced into the receiver for effecting the operative connection of the mechanism with the driving gear.

6. Mechanism for harvesting and topping root crops such as beets and the like comprising a vertical rotatably supported spindle, a rotatable cone supported on the spindle, the cone being hollow and open at its bottom and having an inwardly yieldable wall portion, a housing enclosing the cone and having a side inlet and an outlet, a pair of spaced guide plates disposed at opposite sides of the housing inlet, a closure structure in the space between the plates in spaced relation with the housing inlet, said closure structure, the plates and the cone forming a beet receiving throat, guides for directing movement of a beet top down into said throat, the said yieldable wall of the cone yielding under the pressure of a beet discharged downwardly into the throat whereby the beet may enter between the cone and the wall of the housing, power mechanism for rotating the cone, a horizontally disposed knife at the lower end of said cone and positioned to have the beet top moved against the edge thereof as the beet is carried around between the wall of the cone and the housing, and a linkage mechanism actuated by the inward movement of the yieldable wall

of the cone for effecting the vertical adjustment of said knife.

7. A topping mechanism of the character stated in claim 6, with a vertically movable deflector disposed across the lower part of said throat and adapted to have the beet pressed thereagainst, said vertically movable deflector functioning upon downward movement to establish a driving connection between the cone spindle and the power mechanism.

8. In a topping mechanism for root crops such as beets and the like, a power shaft, a gear operatively connected with and driven by the power shaft, a rotatably supported spindle adjacent to said gear, an oscillatable camming element, a shiftable gear operatively connected with the spindle and movable by the camming element into driving connection with the first gear, a hollow cone body having an open bottom, a central sleeve thorough which the spindle extends and a web connecting the sleeve with the wall of the body, the sleeve being secured to the spindle and the wall of the body being split longitudinally adjacent to the web to provide an inwardly yielding portion, a housing enclosing the conical body and having an inlet opening and an outlet opening, a receiver at the inlet opening of the housing for receiving a beet root in top-down position whereby the beet root body is positioned against the wall of the conical body, a traveling belt forming a side of said receiver for effecting the forcible downward movement of the beet root against the conical body whereby to press in said yieldable wall portion, a movable deflector engaged by the downwardly moving root for actuating the camming element for establishing the said driving connection between the gears to set up rotation of the conical body whereby to move the root body around within the housing toward the outlet opening, and a cutting mechanism for severing the beet top from the root body as the body is moved by the cone within said housing.

9. Mechanism of the character stated in claim 8, wherein said cutting mechanism includes a vertically adjustable knife blade located below the open bottom of the cone body, a pivotally supported arm operatively coupled with the knife blade to effect the raising of the blade upon oscillation of the arm, and a member carried by the arm within the cone body for engagement by the yieldable portion of the cone body to effect oscillation of the arm.

10. A topping mechanism for root crops such as beets and the like, comprising a pair of upright, spaced and inclined guide plates between the upper ends of which a beet root to be topped is deposited, a conical housing having an inlet opening in the wall thereof which is bordered on opposite sides by the lower portions of the guide plates, the housing having an outlet opening, a power shaft extending transversely below the housing, a gear operatively coupled with and driven by the power shaft, a rotatably supported

spindle adjacent to the gear and extending through the center of the housing, a hollow cone body supported upon the spindle and having its lower end open, the cone body further having a radial web extending from the spindle to the wall of the body, the wall of the body being longitudinally split adjacent to the web to provide an inwardly yielding portion, a gear keyed to the spindle for sliding movement thereon for operative connection with the first gear, a shift lever for moving the keyed gear into operative connection with the first gear, a vertically movable beet receiving plate disposed across the space between the lower ends of the guide plates and operatively coupled with said shift lever, said shiftable plate when moved downwardly actuating the shift lever to establish connection between said gears, a spring element normally urging the gears to disconnected relation, a traveling element disposed between the guide plates and in spaced relation with the conical body for forcibly moving a beet root downwardly toward the shiftable plate against the wall of the conical body, a topping knife disposed below the open bottom of the conical body and the housing and supported for up and down movement relative to the bottom of the conical body, and an arm operatively coupled with the knife and movably supported within the lower part of the conical body for actuation by the yieldable portion of the conical body to effect vertical adjusting movement of the knife.

11. A mechanism of the character stated in claim 10, wherein said knife support includes a guide, a post slidable in the guide and rigidly connected with the knife, the said operative coupling between the arm and the knife comprising a link between an end of the arm and the knife carrying post, a portion of the arm lying within the area defined by the lower part of the cone body, and a plate carried by the arm within the cone body in position to be engaged by the yieldable portion of the cone body wall upon inward movement of said portion to effect oscillation of the arm.

45 MARIE E. AMEND,
Administratrix of the Estate of Jacob E. Amend,
Deceased.
